APPARATUS FOR HEAT-TREATING INTERNAL SURFACES OF METAL ARTICLES

Albert Edward Shorter, Sheffield, England, assignor to The Linde Air Products Company, New York, N. Y., a corporation of Ohio

Application May 28, 1942, Serial No. 444,804
In Great Britain June 4, 1941

4 Claims. (Cl. 158—27.4)

1

This invention relates to apparatus for the heat treatment of internal metal surfaces and especially to apparatus for the surface hardening of such surfaces by the application of high temperature heat followed by quenching.

It is an object of this invention to provide apparatus by which internal metal surfaces of relatively small diameter, such as internal bearings, may be uniformly treated; to provide such apparatus by which all portions of the internal surface may be heated simultaneously, and a heating unit adequately cooled; to provide apparatus for treating internal metal surfaces by which high temperature heating flames are directed against such a surface and an auxiliary combustion-supporting medium is supplied to such flames; to provide such apparatus which includes a heat treating device which is accurately located and guided during the heat treating operation; to provide for a relative rotational movement between the heat treating device and the work during such treatment, and to produce more uniform heating and quenching. Other objects and the novel features of this invention will become apparent from the following description and accompanying drawing, in which:

Fig. 1 is a sectional elevation of the preferred form of heat treating device.

Fig. 2 is a transverse section taken along the line 2—2 of Fig. 1.

Fig. 3 is a sectional elevation, illustrating a modified form of heat treating device, in operative position with respect to a surface to be heat treated.

The heat treating device D comprises, in combination, a burner head 10 adapted to be located in juxtaposition with respect to the surface and having longitudinal gas passages therein with radial gas outlets 11 by which high temperature heating flames may be applied to the surface, so as to heat the whole of the surface simultaneously; a quenching unit 12 co-axial with the burner head and having radial fluid discharge outlets 13; and a conduit 14 for the supply of fluid to the quenching unit, the conduit extending through the burner head and acting as a thermal conductor to transfer heat from the burner head to the fluid passing to the quenching unit.

Referring to Figs. 1 and 2, for details of the treating device D, the burner head 10 is secured, as by welding or brazing, to a gas distributing chamber 21 having an inlet 22 adapted to be connected to a pipe 23 supplying gaseous fuel, such as an oxy-acetylene mixture. Extending

2

inwardly into the burner head 10 from the end surface remote from the quenching unit 12, and communicating with the distributing chamber 21, are a plurality of longitudinal gas passages 24 symmetrically disposed with respect to the central longitudinal axis. From each passage 24 there extends a series of the radial gas outlets 11, which are preferably arranged with the outlets of one row staggered with respect to those of an adjacent row. The rows of gas outlets 11 preferably cover in the longitudinal direction a distance slightly less than the length of the bore to be treated, so that the terminal jets at each end do not impinge on the edge of the bore but a short distance from the edge, thereby preventing overheating of the edge which is heated substantially solely by conduction. To reduce the tendency to backfire, each longitudinal gas passage 24 preferably tapers inwardly from the open end as shown in Fig. 2. The burner head 10 is preferably made of highly heat conductive metal such as copper in order that heat may readily be transmitted to the cold fluid which is passed through the conduit 14.

In view of the confined space within which the heat treating device is primarily designed to operate, the conditions for combustion may not be ideal and in order to facilitate combustion, means may be provided for leading an auxiliary combustion-supporting medium to the combustion zone. This means may consist of longitudinally extending passages substantially entirely within the burner head, along which air as the auxiliary combustion-supporting medium may pass by induction to the combustion zone. As shown in Fig. 2, a plurality of separate channels 26 may be provided in the burner head terminating in outlets or orifices 27 interspersed among the gas outlets, these separate channels 26 being supplied with air or other oxidizing gas. For this purpose, a pipe 28, adapted to be connected to an auxiliary supply of combustion supporting gas such as air, extends through the chamber 21 from the upper end thereof and divides into two tubes 29 which lead to channels 26 each having a series of radial discharge outlets 27.

The quenching unit 12 comprises a chamber 30 closed at the end remote from the burner head 10 by a removable plug 31 which permits ready access to the chamber 30 for cleaning purposes. A quenching medium, such as water, is supplied to chamber 30 from conduit 14, supplied by a tube or pipe 32 which extends through chamber 21 to the upper end of conduit 14. In the wall of the chamber 30 are formed the radial outlets 13

for discharging the quenching medium. These outlets are preferably arranged in rows which extend over a distance at least equal to the length of the bore to be treated so as to insure thorough quenching of the whole of the heated surface.

In operation, the inlet pipe 23 is connected to a supply fuel of gas or suitable combustible mixture, the pipe 32 to a supply of cold fluid, and the pipe 28 to a source of compressed air or other combustion-supporting gas. The heating jets issuing from the burner orifices 11 are lighted and the heat treating device thereupon inserted in the bore to be treated, the whole of the bore being heated simultaneously. After a predetermined time interval, sufficient for the surface of the bore to be raised above its critical temperature, the heat treating device is moved longitudinally so as to withdraw the burner head 10 from its operative position and simultaneously to move the quenching unit 12 into the bore to quench the heated surface.

During the whole operation, the cooling fluid supplied to conduit 14 passes through the heat treating device and when the burner head 10 is in operative position, the spraying of the fluid through the quenching orifices 13 serves solely to cool the fluid which has become heated during its passage through the burner head 10 and which may be collected and re-used. When the quenching unit 12 is in operative position in the bore, the burner jets are preferably extinguished so that the cooling fluid reaches the quenching unit 12 very nearly at the supply temperature and therefore serves as a more efficient quenching medium.

When a succession of articles are to be treated, each having one or more bores to be hardened, it is of advantage to mount the articles in turn in a chuck or other rotatable supporting means and an apparatus for the heat treatment of a bearing surface will now be described by way of example with reference to Fig. 3.

A bearing member 35 having a central bore or bearing surface 36 to be hardened is mounted in a chuck, the jaws 37 only of which are shown. The chuck is rotatable about the central longitudinal axis of the bore and a heat treating device constructed as shown in Fig. 1 is mounted within the bore. The details of the heat treating device bear the same reference numerals as in Fig. 1 and require no further description. The chuck is rotated so that the surface 36 may be uniformly heated by the heating flames emitted from the outlets 11 and when the surface has attained the critical temperature, the heat treating device is moved so as to withdraw the burner head 10 from the bore and move the quenching unit 12 into the position occupied previously by the burner head.

In order that the device may be speedily and accurately mounted within the bore suitable locating means may be provided. As shown in Fig. 3, the locating means may comprise a guide member 38 having a central aperture for the reception of a guide pin 39 projecting from the plug 31', which serves as a closure member for the quenching chamber 30. The central longitudinal axis of the guide pin 39 is coincident with that of the burner head 10 and quenching unit

12, and by mounting the guide member 38 so that the aperture therein is also located centrally with respect to the burner head 10 and quenching unit 12, the heat treating device may be accurately mounted within the bore and guided during the movement from the heating to the quenching portions.

The structural details of the heat treating device described above are given by way of example only and may obviously be modified without departing from the invention as defined in the appended claims.

What is claimed is:

1. A device for heat treating an internal surface of a hollow metal article, comprising a burner head adapted to be inserted within the article and having a plurality of longitudinally extending rows of transversely extending outlets for directing high temperature heating flames against said surface; and passages terminating in longitudinally extending rows of transversely extending outlets between adjacent pairs of said outlet rows, for supplying an auxiliary combustion supporting gas to said heating flames.

2. A device for heat treating an internal surface of a metal article, comprising a burner head adapted to be inserted within the article and having a plurality of annularly spaced longitudinally extending combustible gas passages therein terminating in longitudinally extending rows of transversely extending outlets for directing high temperature heating flames against said surface; and longitudinally extending passages substantially entirely within the burner head between adjacent pairs of said combustible gas passages and opening laterally between said rows of outlets for supplying an auxiliary combustion supporting gas to said heating flames.

3. A device for heat treating an internal surface of a metal article comprising a burner head adapted to be inserted within the article and having a plurality of symmetrically disposed longitudinally extending combustible gas passages therein terminating in transversely disposed outlets for directing high temperature heating flames against said surface; a plurality of symmetrically disposed longitudinally extending passages substantially entirely within the burner head each located between an adjacent pair of combustible gas passages and opening between said rows of outlets for supplying an auxiliary combustion supporting gas to said heating flames; and a central longitudinal passage at least coextensive with said rows of combustible gas outlets for the passage of cooling fluid to cool said burner head.

4. A device for heat treating an internal surface of a metal article, comprising a burner head adapted to be inserted within the article and having a plurality of symmetrically arranged longitudinally extending rows of transversely extending outlets for directing high temperature heating flames against said surface so as to heat substantially the whole of said surface simultaneously; and longitudinally extending passages substantially entirely within the burner head between adjacent pairs of said rows on opposite sides of said burner for supplying an auxiliary combustion supporting gas to said heating flames.

ALBERT EDWARD SHORTER.
